(57) **CLAIM**

I claim the ornamental design for a tire, as shown and described.

DESCRIPTION

FIG. 1 is a perspective view of a tire showing my new design;

FIG. 2 is a front view of the tire as shown in FIG. 1;
FIG. 3 is a left-side view of the tire as shown in FIG. 1; and,
FIG. 4 is a right-side view of the tire as shown in FIG. 1.
The broken lines are only for environmental purposes and
form no part of the claimed design.**1 Claim, 4 Drawing Sheets**FIG. 1

FIG. 2

FIG. 3

FIG. 4
